US00D807875S

(12) **United States Design Patent** (10) Patent No.: **US D807,875 S**
(45) Date of Patent: ** Jan. 16, 2018

(54) **COMPUTER**

(71) Applicant: **HEWLETT-PACKARD DEVELOPMENT COMPANY, L.P.**, Houston, TX (US)

(72) Inventors: **Mark Senatori**, Houston, TX (US); **Ilchan Lee**, Houston, TX (US); **Marcus Hoggarth**, Houston, TX (US); **Jack Godfrey Wood**, Houston, TX (US); **Stephen de Saulles**, Houston, TX (US); **Ian Guy**, Houston, TX (US); **Harc Lee**, Houston, TX (US); **Sunny Hwang**, Houston, TX (US)

(73) Assignee: **Hewlett-Packard Development Company, L.P.**, Houston, TX (US)

(**) Term: **15 Years**

(21) Appl. No.: **29/582,966**

(22) Filed: **Nov. 1, 2016**

(51) LOC (11) Cl. **14-02**

(52) U.S. Cl.

USPC **D14/316**

(57) **CLAIM**

We claim the ornamental design for a computer, as shown and described.

DESCRIPTION

FIG. 1 is a perspective view of the claimed design according to a first embodiment in a first position;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is perspective view of the claimed design according to the first embodiment in a second position;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof;

FIG. 14 is a rear elevational view thereof;

FIG. 15 is a perspective view of the claimed design according to a second embodiment in a first position;

FIG. 16 is a top plan view thereof;

FIG. 17 is a bottom plan view thereof;

FIG. 18 is a left side elevational view thereof;

FIG. 19 is a right side elevational view thereof;

FIG. 20 is a front elevational view thereof;

FIG. 21 is a rear elevational view thereof;

FIG. 22 is a perspective view of the claimed design according to the second embodiment in a second position;

FIG. 23 is a top plan view thereof;

FIG. 24 is a bottom plan view thereof;

FIG. 25 is a left side elevational view thereof;

FIG. 26 is a right side elevational view thereof;

FIG. 27 is a front elevational view thereof; and,

FIG. 28 is a rear elevational view thereof.

The ornamental design which is claimed is shown in solid lines in the drawings. The broken lines formed by dashes show unclaimed subject matter and form no part of the claimed design.

1 Claim, 28 Drawing Sheets
